CLAIM

The ornamental design for riser mounted row seats, as shown and described.

DESCRIPTION

FIG. 1 is a front perspective view of riser mounted row seats according to the new design;

FIG. 2 is a side view of the design of the seat in FIG. 1, the opposite side view being a mirror image thereof;

FIG. 3 is a front view of the seat of FIG. 1; and,

FIG. 4 is a rear view of the seat of FIG. 1.

1 Claim, 4 Drawing Sheets
